2 Sheets-Sheet 2

Fig. 2

UNITED STATES PATENT OFFICE.

THOMAS P. SHEAN, OF CHICAGO, ILLINOIS, ASSIGNOR TO SHEAN STEEL WINDOW CO., OF CHICAGO, ILLINOIS.

METALLIC WINDOW CONSTRUCTION.

Application filed September 24, 1919. Serial No. 325,938.

To all whom it may concern:

Be it known that I, THOMAS P. SHEAN, a citizen of the United States, residing at Chicago, in the county of Cook, State of Illinois, have invented certain new and useful Improvements in Metallic Window Constructions, of which the following is a specification.

Metallic window structures now usually installed are made of light gauge material. This lacks both strength and durability, and, although the period of use of these structures since their adoption has been but of limited duration, deterioration is becoming evident, due in large measure to corrosion of the metal.

Furthermore, the light gauge material used is susceptible to easy distortion so that the shape of the windows is easily impaired; in fact, to preserve the shape of the same it is common to fill portions thereof with cement to give the requisite solidity and rigidity thereto to prevent distortion. This filling is a contributing factor to the corrosion above referred to and obviously adds expense to the installation.

Furthermore, by reason of the light gauge material employed the fit of the sash in their frames cannot be properly maintained under changing temperature and atmospheric conditions. For instance, in summer, when the temperature is relatively high, the metal expands and the sash stick, thus precluding free movement of the sash. In winter, with corresponding relatively low temperature, the metal contracts. This opens the joints, admitting cold air, rain dust and snow and precludes maintenance of proper temperature conditions within the space served by the windows.

The present invention, therefore, seeks to provide a metallic window construction of such form, arrangement and adaptation of its parts as to overcome the objections above noted. While designed to be made of heavy gauge material, to provide the required strength, rigidity and durability, the same is such that the frames and sash may be pressed to the desired shapes, and this enables the windows to be produced at minimum expense.

The invention also contemplates an improved form of metallic window wherein provision is made for effecting required adjustments between the frame and its sash,

and also where the sash come in contact with each other, to compensate both for expansion and contraction of the metal. Proper fit and movement of the sash, together with tight joints for the exclusion of the elements, are thereby insured, so that the window is adapted to meet the changing conditions incidental to the change of seasons.

Other objects and advantages of the improvements will be apparent as the nature of the invention is better understood, the invention consisting substantially in the novel construction, combination and arrangement of parts hereinafter fully described, illustrated in the accompanying drawings, and finally pointed out in the appended claims.

While the form of the invention herein shown and described is presented as one embodiment thereof, it is to be understood that the same is merely an exemplification of the invention, so that this illustration is not to be taken in any limiting or restrictive sense.

In the drawings:

Fig. 1 is a vertical transverse sectional view of a metallic window and its frame constructed in accordance with the present invention.

Fig. 2 is a horizontal sectional view through the frame and the sash, and illustrating the relative positions of these parts and the appurtenances for carrying into effect the present invention.

Fig. 3 is a fragmentary top plan view of the sill of the window.

Fig. 4 is a transverse sectional view thereof on the line 4-4, Fig. 3.

Fig. 5 is a detail sectional view of the muntin employed with the sash.

Referring now in detail to the accompanying drawings, the numeral 10 designates the sill of the herein described window. This is cast of metal of the required strength and dimension, and the same is provided at its ends with substantially rectangular seats 11 for supporting the stiles of the window casting. By reference to Figs. 1 and 4 it will be observed that the sill 10 includes a depressed central portion or web 12, which web 12 is connected by a central substantially vertical web 13 and terminal webs 14 with the seats 11 and the central portion of the sill 10 which cooperates with the lower sash. Each of the seats 11 is pro-

vided with a plurality of upwardly extending perforated flanges 15, which provide attaching means for the lower ends of the casing stiles as later set forth.

5 For the purpose of excluding passage of the elements between the sill 10 and the masonry on which it is supported the sill 10 is provided at its under side with a longitudinally extending angle iron 16, the horizontal flange of which has a plurality of transverse slots 17 for receiving attaching screws 18, whereby to connect the angle iron with the sill. Ordinarily, the masonry is formed with a groove 19 that extends crosswise of the window and is filled with cement, the groove receiving a depending flange from the sill. It is difficult, however, to position the sill with its depending flange, due to varying slight differences of position that the groove 19 occupies in relation to the window opening. By adjustably mounting the angle iron 16 on the sill through the medium of the screws 18 and the slots 17, the angle iron may be easily adjusted to accommodate itself to the groove, and thus permit the sill to be mounted regardless of the dimension of the groove 19 or its relative position with respect to the window opening.

10 The numeral 20 designates one of the stiles of the window facing, the lower end of which is supported by one of the seats 11 of the sill 10, and secured to the perforated flanges 15 thereof by screws, rivets or other fastenings. It will be understood that the construction of this stile is duplicated at each side of the window, and said stile is of substantially rectangular form in cross-section. As before stated, it is designed to make the herein described construction of heavy gauge metal, and to press the forms and shapes thereof in order to reduce the cost of production to a minimum. The stile 20, therefore, is pressed to the shape referred to, and the inner edges of the front and rear sides thereof terminate in flanges 21 designed to receive a supporting member 22, which may be of relatively thinner material, for closing the stile 20. The edges of the supporting member 22 are folded about the flanges 21 to secure said member in position thereon, and this member 22 has attached thereto a division wall or partition 23 for separating the sash weights 24 and preventing their interference with each other in the movement of the sashes. These weights 24 may be of any approved construction, being provided with attaching eyes 25, or the like, for attachment of the sash weight cords or chains. It is to be observed that the stile 20 includes a substantially rectangular bead 26 formed at the intersection of the outer wall of the stile and the face of the latter against which the sash are positioned. The inner wall 27 of said bead 26

is inclined with respect to the face of the stile for a purpose to be presently described, so that the bead 26 provides an overhanging shoulder which is utilized in connection with the outer or upper sash for guiding the same.

15 Spaced at a suitable distance from the bead 26 is a guide strip 28, the same being secured to the face of the bead 26 by screws 29, or their equivalent. The guide strip 28 and the bead 26 constitute the outer guides for the respective sash.

20 The lintel of the casing is designated by the numeral 30. This is also of substantially rectangular form in cross-section, being pressed to the desired shape, and said lintel 30 includes a flanged supporting member 31, the edges of which are secured to the front and rear faces of the lintel by riveting or other suitable fastening. Mounted upon the supporting member 31 is an anchoring bar 32, which is substantially Z-shaped in cross-section, the upper flange thereof being employed for supporting the masonry above the casing, where necessary, while the lower flange is adjustably secured to the supporting member 31 by a plurality of screws 33, or their equivalent, mounted in slots 34 formed in the lower flange of the bar 32. By means of the slots 34 the anchoring bar 35 may be adjusted crosswise of the lintel so that the point at which it is attached to the bar 31 may be varied to meet different conditions and positions of the casing.

25 The lintel 30 is also provided with a groove 35 at its under face, which groove extends throughout the length of the lintel and is designed to receive the upper rail of the upper sash. By reference to Fig. 1 it will be observed that the side walls of the groove 35 are convergent upwardly, so that the groove 35 is tapered in cross-section, the purpose of which will presently appear.

30 The numeral 36 designates the lower sash and 37 the upper sash. These are of sectional construction, and while, in the main, they include features common to both, they differ in certain details in order to adapt the same for their proper positioning and movement with respect to the casing. The lower sash 36 includes an outer member 38 and an inner member 39 in its base rail, the inner edges of both of these members being bent inwardly so that when positioned with respect to each other the glass 40 may readily fit therebetween, and in order that the members 38 and 39 may be properly connected the lower rail also includes an upper Z-bar 41 and a lower Z-bar 42. The member 38 is permanently attached to the Z-bars 41 and 42, which may be accomplished by spot welding, riveting or other similar means, but the inner member 39 is detachably connected to said Z-bars for the purpose of permitting the introduction of the glass 40 to the sash and

its replacement when necessary. To this end a plurality of screw fastenings 43 is employed, said fastenings being threaded into the inner flanges of the bars 41 and 42, and thus enabling easy removal of the inner member 39 when such is required. The outer member 38 is of greater dimension in its width than the member 39, thereby providing a depending flange 44 which is designed to contact with the inclined web 13 of the sill 10 when the sash is lowered into closed position in relation to the sill. This flange 44, by reason of the resilient or flexible nature of the material of which the member 38 is formed, will yield slightly when it is brought into contact with said web 13, thereby causing a slight bend in the member 38 approximately at the point designated by the numeral 45. Obviously, therefore, a tight joint between the sash 36 and the sill 10 is insured, and the flange 44 engaging the web 13 of the sill in the manner noted effectually excludes air, dust, rain and snow when the sash is lowered into closed position on the sill. While this construction affords a tight joint, the weather proof character of this joint may also be further insured by means of a weather strip 46 detachably connected to the lower Z-bar 42, as by screws 46a, or their equivalent. Any approved construction of strip may be used in this relation, and its co-operation with the sill 10 provides additionally against passage of the elements at the joint.

The top rail of the lower sash 36 also includes an outer member 47 and an inner member 48, a Z-bar 49 being interposed therebetween. The outer member 47 is connected to the Z-bar 49 preferably by screws 50, the heads of which are countersunk in the outer member 47, and the inner member 48 is detachably connected to said Z-bar by screws 51, or their equivalent, the inner member 48 thereby being readily detachable in order to permit introduction of the glass 40 and its replacement when desired. It is to be observed that the Z-bar 49 has a horizontal plate 52 connected to its inner flange, the outer end of said plate having a depending flange 53, and said flange 53 is spaced from the outer member 47 so as to provide a groove in the top rail of the lower sash for a purpose to be presently described.

Each stile of the lower sash 36 includes an outer member 54 and an inner member 55, with an interposed Z-bar 56. The outer member 54 is fixably connected to the Z-bar 56, preferably by spot welding, although other suitable approved fastenings may be employed, while the inner member 55 is detachably connected to said Z-bar, as by screws 57, or their equivalent, so that the inner members may be readily detachable to facilitate introduction of the glass 40 and its replacement. The inner member 55 is wider

than the outer member 54, so that its outer edge is projected into the guideway formed by the bead 26 and the guide strip 28 of the stile 20 of the casing. This affords a guide flange 58, the extremity of which is deflected in such manner that only the edge of the member 55 contacts with the guide strip 28. This reduces the friction between the member 55 and said guide strip 28, and promotes the easy sliding movement of the sash in the casing. By thus deflecting the extremity of the flange 58 a contact toe 59 is provided.

Suitably connected to the Z-bar 56 is an attaching bracket 60, by means of which the sash weight rope or chain is connected to the sash.

The upper sash 37, as above indicated, partakes generally of the construction of the lower sash. Its lower rail includes an outer member 61 and an inner member 62, and interposed between said members is a channel bar 63 to the outer flange of which the outer member 61 may be spot welded, or otherwise suitably affixed. This outer member 61 also is provided with a horizontal plate 64, the inner edge of which has a deflected flange 65 formed thereon, which flange is designed to enter the groove between the flange 53 and the outer member 47 of the top rail of the lower sash. By reason of the deflection of the flange 65 the same will contact the inner edge of the flange 53 and the outer member 47, thereby establishing a tight joint at the meeting rails of the sashes, and reducing liability of passage of the elements at this point to a minimum. The inner member 62 of the sash 37 is detachably connected to the channel bar 63 by screws 66, and said member is likewise provided with a flange 67 detachably engaged with the plate 64, as by screws 68.

The upper rail of the upper sash 37 includes an outer member 69, an inner member 70, and an interposed Z-bar 71. The member 69 is fixedly connected to the Z-bar 71, as by spot welding or equivalent means, while the inner member 70 is detachably connected thereto by screws 72, or their equivalent. This provides for the introduction and removal of the glass 73 when such is required. The upper edges of the members 69 and 70, in the closed position of the sash 37, are received by the groove 35 of the lintel 30. By reason of the tapered cross-section of this groove these edges are slightly sprung toward each other when the upper sash 37 is moved to closed position, the inclined walls of the groove 35 causing tight frictional engagement with the members 69 and 70, and insuring a tight joint at this point. It will be readily seen that the flexible character of the members 69 and 70 contribute to this fit of the sash when the members enter the groove 35.

The stiles of the upper sash 37 each in-

cludes an outer member 74, and an inner member 75 and an interposed Z-bar 76. The outer members 74 are spot welded or similarly affixed to said Z-bars, while the inner members 75 are detachably connected thereto by screws 77 or their equivalent, and each of the Z-bars 76 of the upper sash is also provided with an attaching bracket 77, similar to the brackets 60, for connection 10 of the sash-weight cord or chain. The outer member 74 of each of the stiles of the upper sash is constructed in a manner similar to the inner member 55 of the lower sash, being extended at its inner edge to provide 15 a flange 78, the extremity of which is deflected outwardly so that the edge thereof only bears against the inclined wall 27 of the bead 26, this deflected edge providing a contact toe 79 similar to the contact toe 20 59, thus reducing friction between the sash 37 and the bead 26 to a minimum.

It has been stated that one of the objects 25 of the invention is to afford adjustment between the sashes and the window casing in order to compensate for expansion and contraction of the metal due to changing temperature. Otherwise, the sash 36 and 37 become liable to derangement, and, therefore, susceptible to sticking in relatively 32 high temperature, and such contraction in low temperature as to open the joints and admit the elements. To provide for this compensation an adjustable guide bar 80 is employed. This bar has each of its sides 35 flanged at an angle to the body thereof to form guide flanges 81, said flanges being spaced from the wall 27 of the bead 26 and the guide strip 28, and thereby providing grooves in which the flanges 58 and 40 78 of the sashes 36 and 37 project. One adjustable guide bar 80 is mounted on each stile of the casing, this being accomplished by a plurality of screws 82, the heads of which are countersunk in the bar 80 with 45 which they are associated, the shank of each screw being provided with a collar 83 to hold the screw in rotatable relation to the bar 80 but prevent detachment of the screw therefrom. These collars 83 also 50 afford bearing surfaces for the adjustable guide bars, and it will be obvious that when the screws 82 are engaged with the stiles 20, proper rotation of the screws will cause relative movement between said bars 80 and 55 the stiles, both towards and away from the same, thus providing for different adjustments of the flanges 81 in relation to the flanges 58 and 78 of the sash. Consequently, if the sash becomes loose by reason of 60 contraction of the metal, or for other reasons, movement of the guide bars 80 away from the stiles may be readily effected in order to bring the guide flanges 81 into 65 closer relation to said flanges 58 and 78, and thus tighten the joint. If, however,

the metal expands, or for other reasons a looser joint is required to facilitate movement of the sash, the guide bars 80 are adjusted towards the stiles, so that the flanges 81 thereof are caused to recede from the 70 flanges 58 and 78 of the sash, whereupon the space in which said flanges 58 and 78 slide becomes enlarged, with a resultant greater freedom of movement of the sash.

The position of the guide bar 80 with respect to the stile 20, as illustrated in Fig. 2, presupposes that condition in which a substantially normal temperature obtains. If, therefore, contraction of the metal takes place, the adjustable guide bar 80 will be moved away from the stile 20, and thus decrease the space between the flanges 81 thereof and the wall 27 and guide strip 28, in order to tighten the joint. When such adjustment has been made, and it be necessary to provide for expansion of the metal, the guide bar 80 will be moved back towards the stile 20, and thus compensate for such expansion.

With the parts assembled in the manner described, and related to each other as outlined, it will be apparent that the usual trim, designated by the numeral 84, may be applied to the casing, and a finished appearance presented to the window.

The space between the outer and inner members of the sash and the interposed supporting bars is filled with putty 85 in order to surround the glass when glazing the sash, and it will also be noted that the inner edges of each of the outer and inner members of the sash are curved towards each other and thereby constitute glazing beads for the sash. These edges, however, are spaced a sufficient distance apart as not to contact with the glass, thus reducing to a minimum liability of breakage due to screwing the outer and inner members too tight, and at the same time providing the requisite joint, through intervention of the putty filling, to exclude 100 the elements.

In Fig. 5 is illustrated the muntin of the sash. This includes an outer bar member 86, an inner member 87, and an interposed Z-bar 88. Preferably, the outer member 86 is spot welded to the Z-bar 88 to provide a fixed connection therewith, although other fixed connection may be employed, while the inner member 87 is detachably connected to said Z-bar by screws 89. The edges of the members 86 and 87 are curved inwardly, similar to the edges of the outer and inner members of the sash, and the space between said members is filled with putty 90 in which to embed the edges of the glass. The edges of the members 86 and 87 are likewise slightly spaced from the glass to prevent breakage of the same, and the glass may be readily replaced or introduced by removal of the member 87 similar to introduction and re-

moval of the edges of the glass to and from the top and bottom rails and stile members of the sash.

It will be observed that the relation of the outer and inner members of the sash renders the top and bottom rails and the stiles thereof open for free circulation of the air. This protects the sash against corrosion, and at the same time enables easy inspection of the sash as occasion may require when the sash are removed from the casing. This also permits repainting of the interior of the stiles and rails of the sash with facility and ease. By reason of the open space between the outer and inner members of the sash these members may be adjusted either towards or away from each other to provide for more loose or a tighter fit of the same where sash connects with the casing. The flanges 53 and 68 also may be bent to tighten or loosen the joint formed thereby.

I claim:

1. In a window construction, the combination of a jamb member affording a guide

channel having a side wall for cooperation with the sash, a rigid guide member adjustably mounted on the jamb member for cooperation with said wall, a movable sash, and a flexible member on said sash arranged for engagement between said wall and adjustable guide member.

2. In a window construction, the combination of a jamb member affording an under-cut guide wall, a rigid guide member adjustably mounted on said jamb member, a sash member movably associated with said jamb member, said sash member including a flexible guide flange arranged for operation between and contact with said under-cut wall and adjustable guide member.

In witness whereof I have hereunto signed my name in the presence of two subscribing witnesses.

THOMAS P. SHEAN.
